DESIGN FOR A COMBINED BOTTLE AND CONTAINER

Charles H. Burger, Jr., New York, N. Y., assignor to Para Ti Corporation, New York, N. Y., a corporation of New York

Application September 17, 1945, Serial No. 122,144

Term of patent 3½ years

(Cl. D58—12)

To all whom it may concern:

Be it known that I, Charles H. Burger, Jr., a citizen of the United States, residing at New York city, in the county of New York and State of New York, have invented a new, original, and ornamental Design for a Combined Bottle and Container, of which the following is a specification, reference being had to the accompanying drawing, forming part thereof.

In the drawing:

Fig. 1 is a top plan view of a combined bottle

and container in open condition showing my new design;

Fig. 2 is a side elevation of my container in closed condition.

The dominant features of my design reside in the portions shown in full lines.

I claim:

The ornamental design for a combined bottle and container, substantially as shown and described.

CHARLES H. BURGER, JR.
